UNITED STATES PATENT OFFICE.

WILLIAM H. DETTER, OF KENTON, OHIO.

CONVERTIBLE PLOW.

SPECIFICATION forming part of Letters Patent No. 276,675, dated May 1, 1883.

Application filed November 17, 1881. (No model.)

To all whom it may concern:

Be it known that I, WILLIAM H. DETTER, a citizen of the United States, residing at Kenton, in the county of Hardin and State of Ohio, have invented certain new and useful Improvements in Convertible Plows; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to that class of plows commonly known as "convertible"—that is to say, in which the parts are so constructed as to adapt the frame for use with cultivators or with subsoil-plows, and as a sulky or walking plow or plows; and it consists, first, in novel means for vertically adjusting the main frame of the carriage upon the carrying-wheels; secondly, in the peculiar construction of the main-frame supports, whereby said supports may be tilted according to the nature of the cultivating implement employed therewith; thirdly, in the peculiar construction of main frame, in combination with its adjustable supports and the carrying-wheels; fourthly, in the construction and combination of parts whereby one or more gangs of shovel-plows or cultivators may be attached to the main frame and used as a sulky-plow; and, lastly, the invention consists in certain details of construction and combination of parts, all substantially as hereinafter fully described.

In the accompanying drawings, Figure 1 is a perspective view of the apparatus when used as a sulky-cultivator. Fig. 2 is a side elevation of the same, one of the carrying-wheels being removed. Fig. 3 is a plan view, showing the apparatus when used with a subsoil plow or plows. Fig. 4 is a side elevation of the same. Fig. 5 is a perspective view of the auxiliary frame with the subsoil-plow attached thereto. Fig. 6 is a transverse section of the cultivator. Figs. 7 and 8 are perspective views of a slight modification in the construction of the frame, and Fig. 9 is a perspective view of the dividing-yoke for the cultivator-beam.

In the above-described figures of drawings like letters of reference are employed to indicate like parts wherever such may occur.

A A' are the carrying-wheels, the latter having an extended or prolonged square axle, a^2 , upon which is mounted a crushing-roller, A^2 , Fig. 3, when a subsoil-plow is used, and which roller is removed from the axle when the plow is used as a cultivator or with shovel-plows. 55 The wheels A A' are mounted on short axles $a' a'$, respectively, formed on bearings B B', that have each a short and a long extension, $b' b$, provided with slots b^2 , by means of which the frame may be adjusted either vertically or longitudinally, according to the position of said frame when the machine is used as a subsoil-plow. 60 65

The frame is composed of two side pieces, F F, of the general form shown—that is to say, of the form of a rectangular triangle the hypotenuse of which is curved, as indicated in the drawings. I have adopted this form to provide the necessary bearing-surface for the journal-bearings B B'. These side pieces, F, of the frame are recessed, as shown at f, and within the said recesses are pivoted the standards F', that are braced together by a rear transverse girt, f'' . From the standards F' extend arched braces f^2 , that serve to support the forward transverse girts, f^3 , of the frame, and said transverse girts f^3 are further braced by bars or braces c', that, together with the arched braces f^2 , form bearings for a rock-shaft, R, hereinafter more fully described. When the 75 frame is made of metal the standards F', transverse girts $f'' f^3$, and the arched braces f^2 may all be cast in one piece, also the recessed side pieces, F, while the braces c', with the toothed sector l, hereinafter described, are made separate and removable from the frame. In practice I prefer this method of construction, for the reason that the parts may be made as light and much stronger than when such parts are made of wood. I do, however, not desire to 80 85 90 95 limit myself to the use of metal only, as wood, or wood and metal, may be employed in the construction of the frame.

When the plow is used as a cultivator, as shown, Figs. 1, 2, and 7, the slotted wheel-bearings B B' stand in a vertical position, and by means of the bolts b^3 said frame, as well as

the plows, may be adjusted vertically on the bearings B B' to regulate the depth of the plowing. The bolts b^3 pass through the slots b^2 in the bearings B B', and through the side pieces, F, and uprights F', bolting these parts rigidly together at the required height. In the drawings I have shown two sets of cultivators having two cultivators each and the necessary cleaners or colters. Each plow-beam 10 C is curved laterally, as shown at c, so that they may straddle the rows of the crop to be cultivated. To adjust or regulate the distance between the two sets of cultivators I employ the following means:

15 E E are yokes, each provided with two vertical slots, e, on opposite sides of a central partition, $e^1 e^2$, of rectangular form. The horizontal arm e^3 of the partition extends forward between the plow-beams, and is pivoted, with 20 the latter, in a yoke or clevis, D. The yokes E E have each a bearing or extension, e^4 , for a transverse brace, E', that may be adjusted by means of the bolts e^4 to regulate the distance between two sets of cultivators, as shown in 25 Fig. 9.

The forward end of the clevis D is enlarged, and forms a bearing for the journal g at the lower end of a hanger, G. The journal g projects some distance below the clevis D, and 30 forms itself a bearing upon which is pivoted a second clevis, H.

In the clevis H is pivoted the lower end of a draft-bar, h, to which is connected a single-tree, the two bars h being connected together 35 by a cross-bar or double-tree, h', which latter is attached to the tongue T by means of a bolt or double-tree hook or clevis, as shown. The double-tree has a series of holes, h², so that the draft-bars h may be adjusted laterally.

40 The journal g of the hanger G above the upper face of the clevis D also serves as a bearing, upon which is pivoted the forward bent arm of the rectangular bars I. The straight arm i, extending rearward, is pivoted upon 45 the inner face of the side pieces, F.

The bent arms i of the bars I are extended some distance beyond their pivotal point, and this extended portion i² forms a bearing for one end of a brace, I', the opposite end of 50 which is attached to the transverse girt f'.

The hanger G, upon one end of which the two plow-beams of a set are hung, is attached to the cross-girt f³ by means of a clevis, G', and nuts g', so as to adapt the hanger, and 55 consequently the plow-beam ends, for lateral as well as vertical adjustment to raise or depress the ends of the plow-beams for purposes well understood, or to move them closer together or farther apart, as the distance between the 60 rows of growing crops may require.

It will be seen, first, that the clevises D form 65 bearings for the plow-beam ends and the dividing-yokes E, on the one hand, and the hangers G, bars I, their braces I', and the draft-bars h on the other hand; secondly, that none of these elements are rigidly connected with

the clevises D or with each other; thirdly, that by means of the hangers G and braces I' the said parts are adjustable upon the transverse girts f³ f', both vertically and laterally, 70 and that when once adjusted and secured in position the parts are held against a vertical movement; fourthly, that although each of said parts is held against vertical movement they are all free to rotate horizontally upon 75 their respective pivots and supports to follow or yield to the lateral movements of the carrying-wheels; fifthly, that the plow-beams, although held at their ends against vertical movement, are adapted to be oscillated vertically in or together with the dividing-yokes upon their pivots in the clevises to enable the plowman to raise said plows out of the ground when meeting obstructions, or to hold them to their work; and, lastly, that this vertical oscillation of the plows takes place both with the dividing-yokes E or independent of the same, the said yokes being slotted, as described, to permit this independent vertical oscillation, and both the yokes and plow-beam ends being 90 pivoted upon the same pivot in the clevises.

By means of this simple construction the various compound movements necessary to the elements of an agricultural implement of this class are obtained.

The attachment of the plows to the main frame is as follows, (see Figs. 1, 2, and 7:) The frame being in the position shown, the rectangular bars I are pivoted to the side pieces, F, by means of bolts, the vertical braces 100 G are attached to the forward transverse girt, f³, and the braces I' to the rear transverse girt, f'. The hitching-bars are then raised and connected with the tongue by means of the double-tree h', as above set forth, and the frame may 105 then be adjusted to the desired height upon the wheel-bearings B B' by means of the bolts b³. When the main frame is employed in conjunction with one or two subsoil-plows the said pieces are first tilted into the position shown in 110 Figs. 3, 4, and 6, when the bearings B B' will be in a nearly-horizontal position. The vertical supports or uprights F' are in this case held in position in the slots f of the side pieces, F, by means of a hand-lever, L, and a toothed 115 sector, l, and by means of bolts l², if desired. The lever L is fitted removably into a socket, l', Fig. 4, on the outer face of one of the slotted and curved side pieces, F, and the toothed sector l is bolted to the front and rear transverse 120 girts, f³ f', and the brace e', thus rigidly connecting the frame with its pivotal supports and permitting of the tilting of said supports to any angle or inclination required to regulate the depth the plow is to enter the soil. 125

In order to balance the frame and plow and relieve the horses from a great part of the weight of the former, said frame may be moved toward or from the carrying-wheels, as the case may be, upon the bearings B B', and secured in 130 the desired position by means of the bolts b³, as plainly shown in Fig. 4. When the frame is

in proper position the crushing-roller A^2 is attached and then the subsoil-plow P , which latter is effected as follows:

K is a frame, provided on its rear ends with 5 trunnions or short shafts k , and on the upper face of its front and rear transverse girts, $l^1 l^2$, with one or more bearings, l^3 , for the reception of a roller or oscillating shaft, S , provided with bearings s for the reception of the subsoil-plow.

10 The plow-beam p carries a removable hand-lever, P' , by means of which the plow may be rolled with the shaft S for the purpose of setting it to the land in hillside or other plowing and locked in position by means of the toothed 15 sector s' .

At or near the forward end the plow-frame K has hangers J , pivoted thereto at one end. The opposite end of the hangers J are pivoted to depending ears j , attached to a rock-shaft, 20 R , that has its bearings upon the arched braces f^2 . This rock-shaft R also carries a hand-lever, M , by means of which and the toothed sector N the forward end of the frame K may be raised or lowered as required to pass obstructions or increase or decrease the depth of 25 the plowing.

It will be evident that the frame K may be pivoted at one end in the side pieces, F , by providing suitable bearings; but I prefer to 30 pivot said frame in a separate brace or transverse girt, O , to impart greater rigidity to the main frame when the subsoil-plow is employed. This detachable brace O , that has bearing-blocks o for the reception of the journals k of 35 the plow-frame K , is bolted to the side pieces, F , by inserting the rectangular projecting arms f^o of said brace O into the recesses f of the side pieces and bolting them thereto, so that the frame K is supported from said brace, and the latter from the side pieces, F , as plainly shown in Figs. 3, 8, and 10.

Q is the driver's seat, attached to the rear transverse girt, f' , upon that side of the toothed sector N nearest to the toothed sector l , so as 45 to bring the hand-levers $L M$ within easy reach of the driver.

From what has been said above it will be understood that when one or more subsoil-plows are used with the frame the following elements of the implement are removed, namely: 50 the cultivator-beam C and parts connected therewith, and the clevises $D H$ and the parts $I I' G h h'$, connected therewith. The side pieces, F , are then tilted into the position shown in Figs. 4 and 6, and secured in that 55 position on the wheel-bearings $B B'$ by means of the bolts b^3 . The crushing-roller A^2 is then mounted upon its square journal a^2 , formed upon the furrow-wheel A' , both rotating together upon the journal a' of the bearing B' , as above set forth.

When the parts described are thus arranged the transverse girt O is bolted to the side pieces, F , with the frame K mounted in the journal-bearings o of said girt, and finally the plow P , with its rocking lever P' , is secured in the

bearings of the roller-shaft S , and held therein by the clevis U , Figs. 5 and 6, from which the colter V is hung, and the plow is ready for operation.

When, on the contrary, the implement is to be converted into a cultivator for use in conjunction with one or more sets or pairs of shovel-plows, then the frame and cultivators are arranged as shown in Figs. 1, 2, and 7, except that the rock-shaft R , its lever M , the lever L , the sectors $l N$, and the braces e' are or may be removed, these parts being, as above set forth, removably connected with the framing.

I have shown in the accompanying drawings, hereinabove described, a construction of frame adapted for use in conjunction with the main carrying mechanism and frame, whereby one or more subsoil-plows may be connected with and operated from said frame. I do, however, not desire to lay any claims in this application for the said auxiliary subsoil-plow frame as constructed, reserving myself the right to make a separate application for patent therefor.

To still further lighten the apparatus when used either as a cultivator or subsoil-plow, and to convert the same into a walking-plow, I provide the side pieces, F , each with a toothed segment, W , having a bracket-bearing, w , for the reception of the rock-shaft R and its hangers j and lever M , as shown in Fig. 8. The rock-shaft R may be provided with the toothed segments R' , that mesh with like segments, W , when the shaft is secured in the bearings w , as shown in Fig. 8^a. The whole of the upper tilting frame is here removed, and the only elements thereof brought into use are the side pieces, F , with their bearings $B B'$, the rock-shaft R , and transverse girt O , as plainly shown in Fig. 8. In this manner I provide means whereby the machine may be used as a walking or riding cultivator or plow, and also means to lighten the framing very materially when said machine is used as a walking plow or cultivator.

It is evident, also, that the arrangement of plow-frame just described may be used as a sulky-plow, in which case the driver's seat Q is attached to the girt O , between the bearings o for the subsoil-plows, or between the beams of the two sets of cultivators, the forward end of which is hung from the rock-shaft R , instead of from the forward transverse girt.

Having fully described my invention, what I claim is—

1. In a convertible plow, the combination, with the independent wheel-bearings $B B'$ and the side pieces, F , of the main frame, adjustably secured thereto and capable of being tilted thereon, of the standards of said main frame and parts connected therewith, pivoted to the side pieces, F , and means, substantially as described, for locking said parts rigidly into position when adjusted relatively to each other, substantially as and for the purpose specified.
2. The combination of the main frame and its

side pieces, F, with the independent slotted bearings B B', the carrying-wheels A A', the latter provided with a square journal, a^2 , and the crushing-roller A², all arranged and operating substantially as and for the purposes specified.

3. The combination, with the bearings B B', having slots b^2 and the bolts b^3 , of the recessed side pieces, F, and the standards F', pivoted 10 within the recesses of said side pieces, substantially as and for the purposes specified.

4. The combination of the bearings B B' and the side pieces, F, of the main frame with the standards F' and the parts connected thereto, 15 to, the sector l and hand-lever L, all arranged for operation relatively to each other, substantially as and for the purposes specified.

5. The combination, with the carrying-wheels A A', their bearings B B', having slots b^2 , and 20 the locking-bolts b^3 , of the side pieces, F, the standards F', the transverse girts f' f³, the braces f², the rock-shaft R, sector N, and lever M, all arranged and operating substantially as and for the purpose specified.

25 6. In a convertible plow, the combination, with the adjustable main frame, constructed as described, its tongue T, and a pair of cultivator-plow beams, of the clevises D H, the draft-bars h, carrying the single-trees, and the cross-bar h', all arranged substantially as and for the purpose specified.

7. In a convertible plow, the combination,

with the adjustable main frame, constructed as described, and a pair of cultivator-plow beams, of the clevis D, and the adjustable hangers G, 35 and the supporting-arms I, all arranged and operating substantially as and for the purpose specified.

8. The combination, with the adjustable main frame, constructed as set forth, and a pair of 40 plow-beams, of the clevis D, arms I, hangers G, and braces I', all arranged and operating substantially as and for the purposes specified.

9. In a convertible plow, the combination, 45 with two pairs of plow-beams and a supporting-frame therefor, of the slotted dividing-yokes E and the adjustable connecting brace or bar E', arranged for operation relatively to each other, substantially as and for the purpose specified.

10. The combination, in a convertible plow, 50 of the adjustable main frame, its tongue, and a pair of plow-beams, of the clevises D H, the adjustable hangers G, the supporting-bars I, braces I', draft-bar h, and cross-bar h', all constructed and arranged for operation relatively to each other, substantially as shown, and for the purposes specified.

In testimony whereof I affix my signature in presence of two witnesses.

WILLIAM H. DETTER.
